(57) CLAIM

We claim the ornamental design for a skin care device, as shown and described.

DESCRIPTION

FIG. 1 Is a front perspective view of a skin care device, showing our new design;

FIG. 2 Is a front view thereof;

FIG. 3 Is a back view thereof;

FIG. 4 Is a right side view thereof;

FIG. 5 Is a left side view thereof;

FIG. 6 Is a top plan view thereof; and,

FIG. 7 Is a bottom plan view thereof.

The broken lines shown represent unclaimed subject matter and form no part of the claimed design.
